UNITED STATES PATENT OFFICE.

JOSEPH B. KISLINGER, OF NEW YORK, N. Y., ASSIGNOR TO MARIE B. KISLINGER, OF NEW YORK, N. Y.

CASE FOR WATCHES, ETC.

Application filed December 5, 1925. Serial No. 73,343.

My invention relates particularly to ornamental cases of the type set forth in my application #721,721 filed June 23, 1924. In such construction the watch movement 5 is mounted in a body formed of ornamental material such as rock crystal, precious or semi-precious stones, pearl shell, onyx or glass colored or shaped to represent precious stones. The body is held by a metal band 10 which partially protects it against injury and yet facilitates removal of the body and replacement in case of accident or when it is desired to employ a body of different color or material.

15 My present invention relates to a simpler and more secure method of connecting the ends of the band to each other and to the swivel sleeve and to the method of adapting the band to bodies of slightly varying size 20 and shape. It also involves improvements in the body ensuring more perfect pieces when made of pressed material such as glass, bakelite, celluloid, or the like.

25 The details of the preferred form and some of the modifications which I consider embody features of my invention will be found illustrated and described herein.

30 Fig. 1 is a perspective view showing the various elements of one form of construction embodying my invention.

Fig. 2 is an enlarged fragmentary transverse section of the assembled parts.

35 Fig. 3 is an enlarged longitudinal sectional view showing the method of securing the parts together.

40 Fig. 4 is a sectional view of a modified form of construction.

Fig. 5 is a longitudinal sectional view of 45 another form of body.

The watch movement may be of any style or shape suitable for the purpose desired, for instance round, oval or rectangular.

This movement is secured in a case 10 having a dial 11 and a back plate 12 held in place in any suitable manner. The watch preferably has a winding stem 13 and crown 14.

50 In my former application the ornamental body consists of a main part of transparent material having a recess for the movement in its rear closed by a hinged back plate. In Figs. 1 and 2 of the present case the body consists of two plates or parts 15 and 16 which are identical and hence interchangeable. Each plate has a recess to

accommodate part of the watch movement. Each recess has a peripheral shoulder such as 17 and 18 to position the dial 11 and case plate 12 respectively. The difference between the thickness of the dial 11 and the shoulder 17 is just sufficient to leave room enough for the free movement of the hands of the watch. Each part has a groove 19 to allow for one half of the stem 13. Each of the parts of the body preferably has a 60 central transparent lens portion 20 bounded by a shoulder 21 of the same diameter as the inner shoulder 18. This not only clearly defines the location of the lens but ensures a 65 uniform pressing action and consequent uniform product when the plates are made of 70 glass, or other pressed material.

The outer faces of the plates 15 and 16 are preferably ornamented or provided with facets and inclined toward the edges which 75 are bevelled at 22, 22. Obviously the dial 11 and back case plate 12 may be ornamented or engraved if desired. So also the faces 23 may be ornamented or marked as desired for instance with monograms or other legends, 80 symbols, or emblems. The face of the dial may be illuminated for instance with luminous point either on the dial or on the inner surfaces of the lens 20.

85 The band 24 is of metal which fits the bevelled edges 22. The ends of the band are provided with ears or wings 25 which project toward each other on the opposite sides to form a pocket to receive the tapered upper end of the body parts 15 and 16. 90 The ends 26 and 27 are shaped to form a bearing for the swivel sleeve 28 which holds the ends together with the band clamped on the body of the case. Each end is provided with annular or tubular extensions such as 95 29 and 30 which overlap each other when the parts are assembled. These tubular members are designed to abut against each other so as to be drawn into alinement snugly when the locking screw 31 is passed 100 through. This screw preferably has a threaded engagement inside the lower tube 29 so as to eliminate the necessity for a nut beneath the tube.

105 The upper part of the screw need not be threaded. The head of the screw 31 may be large enough to overstand the upper edge of the sleeve 28 or a separate washer 32 may be interposed, if desired. The bow 33 has hubs 34 which extend into bosses 35 in 110

- the outer walls of the sleeve 28 and are preferably riveted in place. Preferably the outer edge of the enclosing body 15, 16 is continuously convex so that the band may be clamped smoothly in place. The extension pocket formed by the ears or wings 25 makes allowance for considerable variation in the sizes and shapes of the plates. This is quite necessary when the plates are formed of pressed glass or similar material and even when the plates are cut from precious or semi-precious stones as it is impractical to make the plates always of exactly the same size.
- 15 In the form shown in Fig. 4 the body is formed of two plates, the front plate 40 being thicker than the rear plate 41. In this case the crystal or lens 42 is formed separately and the groove 43 for the winding stem is formed entirely in the back of the main front plate 40 of the body.
- In the form shown in Fig. 5 the body 45 is of one piece of suitable material and has a recess 46 in the front for the watch movement which may be secured in place in any suitable manner and provided with its own crystal. The winding stem may be inserted through the passage 47.
- I claim:
- 39 1. A case construction of the character described comprising a body, a band detachably embracing said body and having two projecting ends with a screw thread between them, a sleeve surrounding said ends and holding them together, a screw seated in said screw thread and having a head over-
2. A construction comprising an ornamental body, a band surrounding said body 40 having abutting ends forming a bearing, an inner tubular member secured to one end, an outer tubular member secured to the other end and overlapping the outer end of the other tubular member, a sleeve 45 mounted on said bearing, and a locking member passing through said outer tubular member and into the inner tubular member for securing the ends together and said sleeve in place.
3. A case frame comprising a metal band adapted to embrace the edges of a detachable body tapered at its upper end, said band having ends adapted to be separated to release the body, and having ears extending toward each other at opposite sides to form a pocket to receive the upper end of the body and detachable means for securing the ends of the band together in alignment.
4. A case comprising a body having a 60 tapered upper end and recessed to form a receptacle, a band detachably surrounding the edge of said body and having upwardly extending ends arranged side by side, said band having ears projecting from opposite 65 sides toward each other below said ends and forming an extended pocket for enclosing the tapered upper end of the body, and means for drawing the ends of the band together in alignment.

JOSEPH B. KISLINGER.
